UNITED STATES PATENT OFFICE.

LAURISTON TOWNE, OF PROVIDENCE, RHODE ISLAND, ASSIGNOR TO THE
LACING BUTTON HOOK COMPANY, OF SAME PLACE.

IMPROVED MACHINE FOR MAKING BUTTON-HOOKS.

Specification forming part of Letters Patent No. **86,473**, dated February 2, 1869.

To all whom it may concern:

Be it known that I, LAURISTON TOWNE, of the city and county of Providence, in the State of Rhode Island, have invented a new and Improved Machine for Making Button-Hooks; and I do hereby declare that the following specification, taken in connection with the drawings making a part of the same, is a full, clear, and exact description thereof.

Figure 1 is a side view. Fig. 2 is a plan. Figs. 3 to 8, inclusive, are detailed parts to be referred to. Nos. 1 to 4, inclusive, exhibit articles made by the machine in its progressive stages from the blank to the button-hook.

The same letters indicate corresponding parts in all the figures.

The machine herein described is especially designed to make the article used in place of eyelets for holding the lacings of shoes and gaiters, known as a "combined hook and button," and for which article of manufacture Letters Patent of the United States were granted to William H. Shurtleff, bearing date June 5, A. D. 1866. The principles of construction which the machine exhibits can also, with suitable modification of the forms of the cutter and dies, be made available for the production of various articles made from sheet metal which require to be swaged by successive operations into a particular shape.

The blank upon which the present machine is intended to operate in order to produce the special article of manufacture named is shown at sketch No. 1. Before being brought to the finished shape shown at No. 4 it is necessary that it should pass successively through the forms shown at Nos. 2 and 3. The machine cuts its own blanks from a metallic ribbon, which may be fed to it by any convenient means. I prefer to wind the ribbon into a coil, and inclose it in a box, Z, Fig. 2, like a barrel for the mainspring of a watch, with the exception that a transverse slit is cut through the side of such box for the passage of the strip of metal. A pair of feeding-rollers, R, Fig. 2, operated by an intermittent pawl-and-ratchet feed, l L, nip the ribbon of metal and feed it along at the rate required to present a fresh surface of such ribbon to the face of the punch, which cuts out a blank each time that it descends. In this

respect the arrangement is like that employed by me in feeding a similar ribbon to the machine for making sheet-metal chain, heretofore patented to me.

The first operation of the machine is to cut from the ribbon a blank, No. 1. This is performed by a cutter, D', whose face is of the same size and outline as that of the blank. This cutter has a regular reciprocating movement given to it by means of a lever, t, to one end of which the stock D of the cutter, suitably guided, is pivoted, the other end of the lever being pivoted to a link which is operated by a cam, 2, on the main shaft O in a well-understood way. In combination with the cutter described there is a female cutter, 3, Fig. 8, into which the end of the male cutter enters as it descends, carrying with it the blank which has been cut out. Upon the return movement of the cutter its face rises clear of the face of the female cutter, so as to permit the ribbon of metal to be drawn along for a sufficient distance over the female cutter to present a fresh surface, as is familiar to all acquainted with the operation of cutting and punching machines. Contemporaneously with the cutting out of the blank, or nearly so, its circular end is struck into the form of a dome, 4, No. 1. This is effected by means of a die, of proper form, cut in the end of a plunger, 5, Fig. 1, which plunger has an upward movement given to it by means of a cam on the main shaft acting through a lever underneath the bed of the machine similar in arrangement to the means described for operating the cutter D'. This plunger moves upward as the cutter D' is moving downward, so that by the time the end of the male cutter has fairly entered the female cutter there will be found a female die ready to act in combination with the cutter to strike up the circular end of the blank into the form of a dome, that portion of the cutter which cuts the circular end having upon its face a dome-shaped protuberance corresponding in form with the die in the end of the plunger 5. There is thus, as the first result of the machine, a piece of metal cut and swaged into the form shown at No. 1. The cutting-punch leaves this blank upon the table 6 and directly in front of the follower J, Fig. 7. This follower is a thin strip

of metal fitted to slide between guides 7 7, affixed to the sides of the table. Its front end is shaped so as to embrace the blank, as shown. Upon the instant that the cutting-punch commences to rise after having cut and swaged a blank the follower J is caused to push the blank forward by the action of the cam P upon the main shaft working through the vibrating lever K, whose forward end is connected by a link with the rear end of the follower. The blank is thus presented to the apparatus, where the subsequent bending and swaging processes necessary to give it the finished shape shown at No. 4 are to be performed. This apparatus, irrespective of its adjuncts, hereinafter to be described, consists of a circular plate or table, A. (Shown full size at Fig. 4.) It is intended that this plate, which is parallel with the bed of the machine and is located at the end of the table upon which the blank rests, shall have an intermittent motion upon its axis, making a complete revolution, with four intervals of rest. Its face is provided with four sets of spring-jaws, s s, occupying four radii let into the surface of the plate, and at equal distances apart. One of these pairs of jaws is always, when the plate is at rest, in line with the path of travel of the follower which pushes forward the blanks, so that each blank, as it is pushed forward, is received by some one of the pairs of jaws, and, being grasped by them near the tip, is held fast until the next operation has been performed upon it.

The necessary revolution of the plate A is effected by means of the cam Q on the main shaft, which actuates a vibrating lever, X, underneath the platform of the machine, Fig. 2. This lever is linked to a ratchet-gear, as shown at Fig. 6, the ratchet-wheel S having fourteen teeth, and is keyed to the shaft of the plate A, such shaft passing through the hollow standard C. The movement of the lever X to position for engagement with another tooth of the ratchet causes a dog, X', pulled by the spiral spring 17, to enter a notch, 18, (shown in dotted lines,) and hold the table A fast while the swaging operation is being performed. Let it be supposed, now, that a blank has been gripped by one of the sets of jaws receiving it as it is pushed forward by the follower J. The two punches or plungers f and e, attached respectively to the stocks F and E, now descend, actuated by the cams upon the two sides, respectively, of the plate 9 on the main shaft. The action of these punches is to bend the blank into the form shown at No. 2, the one striking up the body of the blank, so that the points will stand upright, and the other giving the bend to the shank, it being understood that the edge of the plate A is cut away, so as to allow these, as well as the formers or punches, hereinafter to be described, to perform their respective functions. The effect of the punch or former f being to throw up the pointed ends of the blank, it becomes necessary to provide some means for holding the

blank in its new form, inasmuch as the spring-jaws s s are no longer to be relied on. Accordingly a pair of holding-springs, 10, Fig. 5, are arranged underneath each pair of spring-jaws s s, so that the blank, when bent, will be thrust between them. The location of these spring-holders is best shown in the sectional view of Fig. 4. The plate A now makes a quarter-revolution, a fresh blank is now introduced in the next set of jaws, and the first blank, already in the form of No. 2, is further bent into the form shown at No. 3 by the action of a punch or plunger, r, (shown enlarged to half-size at Fig. 3,) having a movement in a direction parallel with the plane of the table of the machine, induced by a cam, 11, Fig. 2, on the main shaft. The plate A makes another quarter-revolution, a fresh blank is inserted in the next pair of jaws, and the first blank, which is now in the form shown at No. 3, is completely formed into a button-hook (No. 4) by the action of the two formers a and b, Fig. 1, one working from above and the other from below the plate A, through the agency of the cam S upon the counter-shaft T, which, by means of the levers 12 and 13, connected therewith, gives movement contemporaneously to the plungers 14 and 15, from the ends of which, respectively, the formers a and b project.

After the button-hook has been completed the plate A again makes a quarter-revolution. A fresh blank is inserted in the last pair of jaws, and the completed button-hook is borne outward beyond the periphery of the plate A by a sliding plate or discharger, g, Fig. 4, which plate is actuated by a cam-groove, 16, (shown in dotted lines, Fig. 4,) cut in the face of the standard underneath the plate A, a stud-pin projecting from such plate, fitting into such groove, and effecting the movement of the plate in a well-understood way. The shape of this cam-groove is such that before the plate A has completed its next quarter-revolution it will have been drawn back to its former position; but while it is extended beyond the periphery of the plate A, bearing upon its forked end the button-hook, it is obliged, by the act of the plate A in moving toward the first position at which it was when the blank was received by it, to pass between a forked bar, W, concentric with a quadrant of the plate A, by means of which, when the plate A is sheathed, the button-hook will be stripped off and discharged. Underneath each pair of spring-jaws a similar sliding plate or discharger is located, and each in turn, as the plate A is completing its last quarter-revolution, is thrust forward, as before described. During the movement of these plates, so forming a part of the table A, through the second and third quarters of the table's revolution the groove, being in the form of a true circle, does not disturb them in their position.

It will thus be seen that the mode of operation which the machinery above described exhibits consists, first, in the employment of

proper cutting devices for cutting from a strip of sheet metal a blank of the required form; secondly, in swaging the end of such blank dome-shaped; thirdly, in presenting the blanks, so cut and swaged, in succession to the grip of a pair of spring-jaws, of which there are in this instance four sets corresponding in number to the number of operations, including that of discharging the button-hook, which are to be performed, occupying at equal distances apart four radii of a circular horizontal intermittently-revolving plate or table, such plate making a pause of rest after each quarter-revolution; and, fourthly, in swaging the blank into the several forms shown at Nos. 2, 3, and 4 by the action of suitable instrumentalities arranged to act upon the blank in succession, as before explained.

I do not limit myself to the precise structure of the several parts, as described, but mean to include all merely formal variations of structure and arrangement, accomplishing the same mode of operation by equivalent means.

What I claim as my invention, and desire to secure by Letters Patent, is—

1. The combination and arrangement of suit-

able instruments for cutting out the blank, the follower or carrier J, the intermittently-revolving table A, having holding-dies constructed as described, and the double-acting plungers or formers e and f, substantially as described.

2. The combination and arrangement of the intermittently-revolving table A, with holding-dies constructed as described, the double-acting plungers or formers e and f, and the radially-moving plunger or former v, substantially as described.

3. The combination and arrangement of such intermittently-revolving table A, with holding-dies constructed as described, double-acting plungers or formers e and f, radially-moving plunger or former v, and the two coacting formers a and b, substantially as described.

4. The discharger g, operated as described, in combination with the stripping-fork W, or its equivalent, for the purpose of discharging the finished button-hook, substantially as herein set forth.

LAURISTON TOWNE.
